(57) **CLAIM**

I claim the ornamental design for a glass panel for a canopy for a vehicle, truck, or the like, as shown and described.

DESCRIPTION

FIG. 1 is a front perspective view of an embodiment of a glass panel for a canopy for a vehicle, truck, or the like showing an embodiment of my new design;

FIG. 2 is a front elevation view thereof;

FIG. 3 is a rear elevation view thereof;

FIG. 4 is a rear perspective elevation view thereof;

FIG. 5 is a left side elevation view thereof;

FIG. 6 is a right side elevation view thereof; and

FIG. 7 is a right side view thereof.

FIG. 8 is an exploded perspective view of the glass panel for a canopy for a vehicle, truck, or the like, shown in the environment of a wing door for the side of a canopy for a vehicle, truck, or the like and latches; and,

FIG. 9 is a front elevation view thereof.
